CLAIM

The ornamental design for a conically shaped ice fishing box having an indicator mounted on a removable reel assembly, as shown and described.

DESCRIPTION

FIG. 1 is a top perspective front view of a conically shaped ice fishing box having an indicator mounted on a removable reel assembly showing my new design;

FIG. 2 is a back view of FIG. 1;

FIG. 3 is a left end view of FIG. 1;

FIG. 4 is a top view of FIG. 1; and

FIG. 5 is a bottom view of FIG. 1.

*FIG. 1**FIG. 2**FIG. 3**FIG. 4**FIG. 5*
